UNITED STATES PATENT OFFICE.

WILLIAM FORD STANLEY, OF SOUTH NORWOOD, ENGLAND.

ROTARY ENGINE.

SPECIFICATION forming part of Letters Patent No. 707,174, dated August 19, 1902.

Application filed April 10, 1901. Serial No. 55,148. (No model.)

To all whom it may concern:

Be it known that I, WILLIAM FORD STANLEY, engineer, residing at Cumberlow, South Norwood, in the county of Surrey, England, 5 have invented new and useful Improvements in Rotary Engines, of which the following is a specification.

The object of my invention is to construct a rotary engine that shall have less wearing 10 parts than heretofore and to provide means for taking up whatever wear does take place; and to carry my invention into effect I construct my improved rotary engine as follows.

In the accompanying drawings, Sheet 1, 15 Figure 1 is an elevation, partly in section, and Fig. 2, a plan with part of frame and fly-wheel removed, of the complete engine. Sheet 2: Fig. 3 is a sectional plan through *a a* of Figs. 1 and 4, and Fig. 4 is a sectional elevation through *b b* of Fig. 3.

Similar letters denote corresponding parts throughout the drawings.

The parts of this engine comprise a clear circular groove or chamber of angular or preferably of approximately square section A, 25 turned out of a casting of metal at a distance from an axis B, to which it is concentric. The circular groove of angular section is partly covered by a disk or flange C around 30 the axis and a flange D outside this, placed at such a distance concentrically to it that it may leave a narrow circular aperture E into the chamber A, that is formed by the circular groove of angular section and its disk and flange covers C and D. The axis B of the 35 engine has a clear free way through the center of flange-cover C and carries with it an upper covering-disk or framed ring F, which is fitted to accurately cover the aperture E, 40 so that it makes the concentric chamber it covers steam or gas tight. This covering-disk F carries one or more pistons G, attached to it by means of a web or webs H through the aperture E. The pistons G fit the chamber 45 so that they can move around within it by the pressure of the steam or other fluid or the explosion of gas upon one side of them. Within the chamber sets of duplex, triplex, or multiplex valves I are constructed of the 50 number of sets to the pistons employed in the engine. These valves are formed of light flaps, which meet and close the angular aper-

ture of the ring-chamber at a firm angle. If the valves employed are duplex, which they will be for small engines, they open into recesses J, laterally into the sides of the ring-chamber A. If they are triplex for large engines, two open laterally and one into a recess in the part farthest from the aperture into the ring-chamber; if multiplex, one flap to 55 each angular surface in either case, so as to allow a piston to pass them. Each piston is so formed by curvature of its sides that it presses open the two or more flaps of the valves by a smooth motion, retaining the chamber 60 approximately steam-tight during the time it is pressing them open. The back part of the piston is so formed by its curvature that when its center has passed the flaps they close, by means of springs K or otherwise, smoothly by 65 pressure upon the curves of the piston. The steam, gas, or other fluid pressure is admitted 70 intermittently behind the direction of movement of the piston in a manner that the piston may be propelled by it. This is effected 75 by means of an exterior slide-valve or its mechanical equivalent, which is constructed to cut off pressure at the time the pistons are passing the valves, or, in the case of steam, earlier. These exterior slide-valves are 80 constructed as follows: A small chamber L is fitted between the steam-inlet pipe and the ring-casing of the chamber A, and a valve M moves in this small chamber or valve-box over a face on the outside of the ring-casing. 85 The movement of this valve M by the valve-rod N opens and closes the aperture O, which leads to another small chamber P under the ring-chamber A, and holes Q lead from this chamber P into the ring-chamber A. The 90 movement of the valves is effected by means of cams R upon the covering-disk F, which depress the valves by coming in contact with rollers S, mounted upon the top of the valve-rod N. This opens the ports to admit steam or 95 other fluid pressure, and when the cam R has rotated a sufficient distance to pass the rollers S the valves are raised, so as to close the ports by means of springs T. The exhaust is arranged by making port-holes U at the back 100 of the flap-valves in the ring-chamber A. These are left open to atmospheric pressure or the minus pressure of a condenser.

When this rotary engine is constructed for

vertical motion, as it would be for driving a dynamo, the lower bearing W of the axis of the engine terminates in a cup of oil or other lubricant, which cup is made adjustable for 5 height to compensate for wear of the pistons. In this case the open annular space E between the flanges C and D is closed partially or entirely by the gravity of the covering-disk F and the fly-wheel V, mounted upon the shaft 10 B, being made sufficiently heavy to overcome the pressure employed, or a spring may be used in place of gravity.

When the engine is used with the shaft horizontal, the pressure of spring-flanges or 15 equivalent means is employed to close the covering-disk F to keep it steam or gas pressure tight.

The approximately square groove or chamber A, which forms a ring-casing, is preferably made very slightly tapered at the sides, so that any wear that takes place in the pistons or groove in which they work may be taken up by simply lowering the bearing W of the vertical axis and reducing the top of 25 the sides of the groove, so that the covers are let down to compensate for the amount of wear that has taken place.

Having now particularly described and ascertained the nature of my said invention and 30 in what manner the same is to be performed, I declare that what I claim is—

1. In combination with a ring-casing having a channel, pivoted flaps extending across said channel from opposite sides and bearing 35 against each other at their adjacent ends, said channel being of tapered cross-section, a pis-

ton similarly tapered and having curved sides against which the flaps work, substantially as described.

2. In combination in a rotary engine, a ring-casing having a channel therein, a piston working in said channel, a covering-plate above the channel connected with the piston and valve mechanism comprising a valve and a cam R attached to the covering-plate and 45 arranged to operate the valve, substantially as described.

3. In combination, a ring-shaped casing having a channel therein, a piston in said channel, a shaft extending down through the casing, 50 means for connecting the shaft with the piston extending down into the channel of the ring-shaped casing and an adjustable bearing for the lower end of the shaft whereby the piston may be adjusted vertically in respect 55 to the channel, substantially as described.

4. In combination, a ring-shaped casing arranged horizontally, a shaft extending vertically and axially of the casing, a covering-plate, a piston connected with said covering-plate and extending into the channel of the ring-shaped casing and a fly-wheel on the shaft, the weight of the same tending to keep the covering-plate bearing upon its seat to 60 keep the annular channel closed, substantially 65 as described.

In witness whereof I have hereunto set my hand in presence of two witnesses.

WILLIAM FORD STANLEY.
